UNITED STATES PATENT OFFICE.

DAVID F. HAYNES, OF BALTIMORE, MARYLAND.

DESIGN FOR A EWER OR JUG.

SPECIFICATION forming part of Design No. 23,726, dated October 23, 1894.

Application filed September 19, 1894. Serial No. 523,498. Term of patent 3½ years.

To all whom it may concern:

Be it known that I, DAVID F. HAYNES, a citizen of the United States, residing at Baltimore, Maryland, have invented and produced a new and original Design for a Ewer or Jug, of which the following is a specification, reference being had to the accompanying drawings, forming a part thereof.

Referring to the said drawings, Figure 1 is an exterior side elevation of the ewer, and Fig. 2 a top view of the same.

I describe the ewer or jug as follows: Its base A is circular, and the body B is egg-shaped, except that the ends are cut off so as to produce a frustum, which is comprised between the base A and the line x—x. From the line x—x begins the neck C which first falls in, and is then flared out, forming a regular curve, and this neck at the front is formed into a lip D. The part a in the rear of the body conforms in shape with the lip D but is somewhat lower, and from it extends the handle E which has a foliated decoration.

The upper edge F of the ewer as seen from the side, is scalloped, and where the two boundary curves meet is a small circular inlet b.

At y—y, is a bead and between the bead and the line x—x, is a fimbriated design in relief.

The lower part of the body B has a band G with flutes c having in them fingers d in relief. Between the band G and the line x—x the body is covered with a representation of wild roses or primroses in relief.

The body is diagonally crossed by a band H decorated the same as the remaining portion of the body, except that the flowers are enlarged.

I claim as my invention—

The design for a ewer or jug as herein shown and described.

DAVID F. HAYNES.
